UNITED STATES PATENT OFFICE.

ERWIN W. LAMB, OF LANSING, MICHIGAN.

DESIGN FOR A LAMP.

49,996.

Specification for Design.

Patented Dec. 5, 1916.

Application filed October 20, 1916. Serial No. 126,802. Term of patent 7 years.

To all whom it may concern:

Be it known that I, ERWIN W. LAMB, a citizen of the United States, residing at Lansing, in the county of Ingham and State of Michigan, have invented a new, original, and ornamental Design for Lamps, of which the following is a specification, reference being had to the accompanying drawing, forming part thereof.

The figure is a perspective view of the lamp, showing my new design.

I claim:

The ornamental design for a lamp, as shown.

ERWIN W. LAMB.

Witnesses:

J. W. BAILEY,
CHAS. A. FERGUSON.
